UNITED STATES PATENT OFFICE.

CHARLES P. ALEXANDER, OF CLEVELAND, OHIO.

DIMMER.

Application filed November 3, 1923. Serial No. 672,576.

To all whom it may concern:

Be it known that I, CHARLES P. ALEXANDER, a citizen of the United States, residing at Cleveland, in the county of Cuyahoga and 5 State of Ohio, have invented certain new and useful Improvements in Dimmers, of which the following is a specification.

This invention relates to improvements in dimmers for automobiles and other types of 10 head lights and has for an object to provide a shield readily attachable to a lamp and so positioned and shaped as to prevent the usual objectionable glare and at the same time retain the illuminative efficiency of the head- 15 light.

Another object is to provide a dimmer of this nature wherein is included reliable means whereby the relative position of the 20 dimmer and lamp is kept constant, thus preventing breaking of the bulb or lamps.

Other objects will be in part obvious and in part pointed out hereinafter.

In order that the invention and its mode 25 of operation may be readily understood by persons skilled in the art, I have in the accompanying illustrative drawings, and in the following detailed description based thereon set out one possible embodiment of the same.

In these drawings: 30 Fig. 1 is a view illustrating the application of the dimmer to a headlight.

Fig. 2 is a front elevation of the invention as shown in Figure 1;

Fig. 3 is a detail longitudinal section of 35 the shield in operative position.

Fig. 4 is a sectional view taken substantially on the line 4—4 of Figure 3; and

Fig. 5 is a detail showing the clip carried by the shield.

Having more particular reference to the drawing throughout which similar characters of reference designate similar parts, my improved dimmer may be stated as including a shield 6 which is somewhat spoon-shaped, having its forward end 7 of such a length as to extend considerably below the center of the bulb or lamp B, thereby covering a major portion thereof. As illustrated in Figures 1 and 4, the opposed longitudinal sides are cut away or curved longitudinally upward to permit the light rays from the bulb, to strike the reflector of the headlight and increase the active reflective surface. Furthermore, the inner face of the shield 6 is finished to provide a reflecting surface.

In order to provide a desirable attaching means, I have formed the rear end of the shield so as to permit welding or riveting a substantially inverted U-shaped spring clip 9, which takes over the socket or other part 60 of the headlight as indicated in the drawing.

Ordinarily the forward end of the shield would tend to drop and due to continual vibration would break the bulb. To overcome 65 this, I have arranged upon the said front end portion of the shield a light metal ring 10 having an integral finger for attachment to the inner face of said shield. As shown, this ring is of less diameter than the bulb and receives a portion of the front end of said bulb 70 and retains the shield and bulb in spaced relation.

This shield is arranged upon the upper side of a bulb and as stated exposes a 75 major portion of the longitudinal sides of the bulb, thereby resulting in only a slight reduction of the illuminating efficiency of the light, while the forward end of the shield is extended downwardly to cover a major portion 80 of the front end of the bulb and prevent the forward projection of light rays at a height sufficient to blind a person being approached.

Certain changes in some details of construction may be resorted to and such of these changes as fall within the scope of the appended claim, I consider my invention.

I claim:

1. A device of the character described, 90 comprising in combination, a reflector, a socket, a lamp in the socket, a shield for the lamp including a main body portion arranged over the upper side of the lamp and having its side edges terminated above the 95 longitudinal center of the lamp, the forward end of the body portion being curved downwardly below the center of the lamp and spaced therefrom, a supporting ring depending from the inner face of the shield and 100 adapted to receive a portion of the front end of the lamp and retain the shield and lamp in spaced relation, and a connection between the rear end of the shield and the socket.

2. A device of the character described, 105 comprising in combination, a reflector, a socket, a lamp in the socket, a shield for the lamp including a main body portion arranged over the upper side of the lamp and having its side edges terminated above the 110

longitudinal center of the lamp, the forward end of the body portion being curved downwardly below the center of the lamp and spaced therefrom, a supporting ring depending from the inner face of the shield and adapted to receive a portion of the front end of the lamp and retain the shield and lamp

in spaced relation, the rear end of the shield being reduced and transversely curved to snugly engage the socket, and a substantially inverted U-shaped spring clip carried by the reduced end and engageable over the socket. ¹⁰

In testimony whereof, I affix my signature.
CHARLES P. ALEXANDER.
